UNITED STATES PATENT OFFICE

171,182

TYPEWRITER AND MULTIPURPOSE DESK

William James Bargen, Waukegan, Ill.

Application April 13, 1953, Serial No. 24,457

Term of patent 14 years

(Cl. D33—7)

To all whom it may concern:

Be it known that I, William James Bargen, a citizen of the United States of America, residing at Waukegan, in the county of Lake and State of Illinois, have invented a new, original, and ornamental Design for a Typewriter and Multipurpose Desk, of which the following is a specification, reference being had to the accompanying drawings, forming a part thereof.

In the drawings:

Figure 1 is a side perspective view of a typewriter and multipurpose desk showing my new design,

Figure 2 is a front and side perspective view,

Figure 3 is a rear perspective view thereof as the desk appears when used with the top and guard in raised position; and

Figure 4 is also a rear perspective view as in Figure 3, but with the typewriter support in operative position.

I claim:

The ornamental design for a typewriter and multipurpose desk, as shown.

WILLIAM JAMES BARGEN.
